SOUND-PRODUCING DEVICE

Application filed August 7, 1926. Serial No. 127,877.

My invention relates to sound-producing apparatus, and it has particular relation to such apparatus wherein a relatively small diaphragm is actuated by electromagnetic means.

In order to satisfactorily reproduce both vocal and musical sounds, a diaphragm is desirable which is capable of radiating equally well all the frequencies involved.

10. Plane diaphragms of the usual type have been found unsatisfactory, as they have a pronounced tendency to accentuate those tones lying at or near their own natural frequencies. Diaphragms having large areas, such as cones and the like, have been used with a certain amount of success, but, even with them, many undesirable sounds are produced which are often caused by inertia reactions between the actuating means and the 20 diaphragm.

It is an object of my invention to provide a diaphragm which gives an equally good response over a wide range of frequencies, having no pronounced natural period of its 25 own within the range of the frequencies which are to be reproduced.

Another object of my invention is to so construct the connection between the actuating means and the diaphragm of a loud 30 speaker that it shall not rattle or set up undesirable frequencies.

Another object of my invention is to provide means whereby the response curve of a 35 loud speaker may be corrected with minimum effort.

Another object is to provide a diaphragm which shall be extremely light in weight.

Another object is to provide a diaphragm in two sections, one of which shall be utilized 40 for introducing a correction factor into the response curve.

Another and further object is to provide a new and improved method of cementing a metallic diaphragm to a supporting element.

45. I attain these objects and others which will be more fully explained later by so constructing a diaphragm that it will be responsive, as a whole, to movements of the actuating means representing sounds of large amplitude and low frequency and will also, re-

spond locally to movements representing sounds having very high frequencies.

In order to obtain a level response curve, I may add to a composite diaphragm, an element which controls the output to the atmosphere of that portion responsive to the higher frequencies.

I interpose also, between the diaphragm and the actuating means, a connection which absorbs all radial components of the movement of the driving means, thereby preventing such components from setting up undesirable double-frequency vibrations in the diaphragm. This connection delivers only purely rectilinear movements to the diaphragm. I am thus enabled to provide a vibrating system which, as a whole, is evenly responsive to the entire band of frequencies involved in speech and music.

In order that my invention may be more 70 fully understood, reference is now made to the accompanying drawings and to the following description.

Fig. 1 is an elevational view, partly in section, of a preferred form of my invention, 75 in which the actuating means is indicated diagrammatically.

Fig. 2 is a view, in perspective, of a modified form of connection between the actuating means and the diaphragm.

Fig. 3 is an elevational view, partly in section, of a modified form of connection.

Fig. 4 is a sectional view taken along the line IV—IV of Fig. 3.

Fig. 5 is a view of a portion of the cover 85 plate of the diaphragm, showing a modification.

As illustrated in Fig. 1, a diaphragm 1 is mounted for vibration in a housing 2 and is operatively connected to an electromagnetic actuating means comprising a balanced armature 3 suspended between the pole piece NN and SS of a permanent-magnet system by means of a torsion spring 4. The diaphragm comprises a portion 5 which is trumpet-shaped in cross section and which is preferably spun or stamped from a very light metal, such as aluminum. For best results, this portion of the diaphragm should have a wall of such shape as would be given by the 100

rotation around an axis of an exponential curve lying in the plane of said axis. The lower flaring portion of the trumpet-shaped element 5 is flattened out into an annular mounting rim 7 provided with a plurality of perforations 8 therethrough.

The upper or small end of the portion 5 is closed by a wall 9 pierced by a mounting hole through which projects a clamping bolt 10 provided with a bowed washer 11 and a locknut 12. Positioned around the clamping bolt 10 is a cushion of resilient material 13, the whole assembly of cushion and clamping bolt passing through an opening in the armature 3. The head 14 of the clamping bolt is preferably made concave in cross section, and, under the retaining washer 11 and the head 14, a material, such as shellac, may be applied for pressure-equalizing and locking purposes.

Associated with the lower flaring portion of the element 5 is a cover plate 15 provided with a central opening 16 or series of openings. The periphery of this cover plate 15 is flattened into an annulus 17 corresponding to the mounting rim of element 5, which annulus 17 is provided with a plurality of perforations 18.

A thin annulus 19 of high-grade rubber, or similar material, leather, fabric or the like, is positioned between the perforated flanges 7 and 17 and is held in place by rubber cement or moisture-proof glue. Overlying each flange may be placed rings 20 which will be firmly united thereto by the cement exuding through the perforations 8 and 18. This type of connection is somewhat analogous to riveting, and is extremely firm and durable.

The annulus 19 is secured between the elements 21 and 22 which are united together by screws 23 to form a diaphragm chamber having an outlet 24 to the atmosphere.

The diaphragm assembly I have thus far described I term a "pseudo-plunger," by that designation meaning a diaphragm all parts of which do not move in strict unison when subjected to a driving force applied at the small end of the trumpet-shaped element. Driving forces having low frequency and large amplitude are transmitted by the rigidity of the element 5 to the assembly as a whole. On the other hand, forces having a very high frequency tend to cause the element 5 to vibrate locally and to emphasize the resonant frequency of the chamber defined by the elements 5 and 15 of the diaphragm.

In order to take advantage of the fact that the portion 5 of the diaphragm tends to vibrate locally in response to high frequencies, the cover plate 15 is provided with an opening 16 or a series of openings which I contemplate making variable in size by adjustable means, or by means of plugs of material, such as felt, cotton, or the like. When

the opening 16 is relatively unobstructed, it is apparent that the higher frequencies generated in the element 5 have a free passage to the outside air by way of the sound opening 24.

The chamber defined by the interior walls of the element 5 and the cover plate 15 will usually be resonant to some one frequency and this characteristic of resonance is also of importance when the response curve is to be modified.

By providing the opening 16, or a series of openings, in the cover 15, I am enabled to modify the effect of the enclosed resonance chamber on the output of the device. If the response curve is poor for the higher frequencies, these openings may be large and unobstructed; if the curve shows a preponderance of the higher frequencies, these holes may be closed or may be provided with a damping material.

The cover plate 15, while desirable as an adjunct to small diaphragms of the type used in phonographs, or in loud-speakers provided with horns, is not essential with large diaphragms of the type that are freely exposed on both sides to unconfined air when in use. I have found that large diaphragms having an exponential curvature, instead of being made conical as is customary, give a sufficiently even response to a plurality of different actuating frequencies without the necessity of resorting to the modifying cover plate.

By reason of the resilient mounting 13, radial components of the movements of the armature 3 are, to a large extent, absorbed and damped out before reaching the diaphragm. This is decidedly advantageous, as such movements tend to set up parasitic vibrations in the diaphragm which manifest themselves as hissing or other unpleasant sounds in the output.

By concentrating the restoring force in the spring 4, and by mounting the diaphragm so that transverse strains are not transmitted thereto, the quality of the output is greatly improved.

In Fig. 2 I have illustrated a modified form of connector for use between the driving means and the diaphragm. When this type of connector is employed, the upper portion 5 of the diaphragm is provided with two oppositely extending ears 25. The armature 3, instead of having an opening therethrough, is provided with concave portions 26. Between the armature and the ears 25 is placed a resilient cushion 27 and directly below these ears are other resilient cushions 28, the ears being held firmly against the lower portion of the armature by means of a spring element 29 of C shape which exerts a pressure on the upper side of the armature through a cushion 30. This type of connector prevents bending moments from being

transmitted from the armature to the diaphragm while efficiently transmitting stresses along the axis of the trumpet-shaped portion 5, and is also self-adjusting.

5 In Figs. 3 and 4 is shown a modified form of the connector assembly of Fig. 1. A plurality of cups 31 and 32 having integral central screws 33 and 34 are held together by means of flexible spring elements 35 and 36 10 which are soldered into slots in each cup, as illustrated.

The space between the cups 31 and 32 is occupied by a resilient cushion 37 of rubber or analogous material under a slight amount 15 of pressure. The screw 33 projects through an opening in the diaphragm and is held in position by a locknut 38, while the opposite screw 34 projects through an opening in the armature 3 and is locked in place by means 20 of a nut 39. The connecting springs 35 and 36, because of their flexibility, permit slight angular movements of the armature 3 with reference to the diaphragm 5. Such movements are, however, damped by the resilient 25 cushion 37 and do not set up vibratory motions in the diaphragm. Direct thrusts along the line IV—IV are transmitted by the springs 35 and 36, which are relatively stiff along their longitudinal axes.

30 A sound reproducer constructed according to my invention has a remarkably even response, none of the frequencies commonly present in speech and music being unduly accentuated.

35 In addition, my device is quite free from the parasitic hissing sounds which mar the output from loud speakers provided with plane diaphragms, or large diaphragms of the cone type.

40 Although I have illustrated and described certain specific forms of my invention, obvious modifications will suggest themselves to others skilled in the art. My invention is accordingly not to be limited except insofar 45 as is necessitated by the prior art, or by the following claims.

I claim as my invention:

1. In a sound-producing device, a diaphragm comprising a plurality of elements 50 separated by a continuous annular resilient cushion.

2. In a sound-producing device, a diaphragm comprising a plurality of elements separated by continuous annular resilient means, the diaphragm elements defining a 55 partially closed chamber.

3. In a sound-producing device, a composite diaphragm comprising a section responsive mainly to low frequencies only and a section responsive in substantial degree to both low and high frequencies.

4. In a sound-producing device, a composite diaphragm comprising a plurality of 60 elements, cushioning means between said ele-

ments, one of said elements having walls curved exponentially.

5. In a sound-producing device, a composite diaphragm comprising a plurality of 70 elements in juxtaposition, the inner walls of said elements defining a resonance chamber, and means whereby the properties of said chamber may be utilized to modify the sound produced by said device.

6. In a sound-producing device, a composite diaphragm comprising elements defining a resonance chamber, an opening in a wall of said chamber, and means for adjusting the characteristics of said opening.

7. In a sound-producing device, a composite diaphragm comprising elements defining a resonance chamber, and means for modifying the resonance characteristics of said chamber.

8. In a sound-producing device, a composite diaphragm comprising elements defining a resonance chamber, means for modifying the characteristics of said chamber, and means having a low natural period for mounting said diaphragm in a support.

9. In a sound-producing device, a composite diaphragm comprising elements defining a resonance chamber, means for modifying the characteristics of said chamber, means having a low natural period for 95 mounting said diaphragm in a support, and means for driving said diaphragm.

10. In a sound-producing device, a composite diaphragm constituting a pseudo-plunger.

11. In a sound-producing device, a diaphragm comprising elements defining a semi-closed chamber, driving means coupled to said diaphragm by a resilient coupling and flexible means for mounting said diaphragm 105 in a support.

12. In a sound-producing device, a diaphragm comprising elements defining a semi-closed chamber, one wall of said chamber having a convex cross-section and another 110 wall of said chamber having a concave cross section when viewed from the interior of said chamber.

13. In a sound-producing device, a diaphragm comprising elements defining a 115 chamber, the walls of one portion of said chamber having a shape such as would be given by the rotation around an axis of an exponential curve lying in the plane of said axis.

14. In a sound-producing device, a diaphragm comprising a wall of such shape as would be given by the rotation around an axis of an exponential curve, driving means, and means for attaching said driving means to 125 said element so that the driving force is applied thereto only along said axis.

15. In a sound-producing device, a diaphragm comprising an element having a wall of such shape as would be given by the rota- 130

- tion around an axis of an exponential curve, actuating means so associated with said element that force is transmitted thereto along said axis, an element having low restoring force for mounting said diaphragm, whereby high-frequency vibrations will set up waves in said element while low-frequency vibrations will tend to move said diaphragm as a whole.
16. In a sound-producing device, a diaphragm comprising a plurality of imperforate metallic elements associated by resilient cushioning means.
17. In a sound-producing device, a composite diaphragm comprising a trumpet-shaped portion flaring outwardly into an annulus provided with a plurality of openings therethrough, a second portion having an annular peripheral part having a complementary relation to the first mentioned annulus and also being provided with openings, and mounting means between said portions.
18. In a sound-producing device, a composite diaphragm comprising a trumpet-shaped portion flaring outwardly into an annulus provided with a plurality of openings therethrough, a second portion having an annular peripheral part having a complementary relation to the first mentioned annulus and also being provided with openings, and mounting means cemented between said portions.
19. In a sound-producing device, a diaphragm comprising a trumpet-shaped section flaring outwardly into a rim adapted to be affixed to mounting means, and a cover for said flaring portion having a restrictable opening therethrough.
20. In a sound-producing device, a diaphragm comprising a plurality of sections in juxtaposition, a plurality of registering openings through opposite sections of said diaphragm, mounting means between said sections, and cementing means for holding said diaphragm sections and said mounting means together.
21. In a diaphragm adapted to be used in sound-producing devices, a portion so shaped that it will yield under inertia stresses and a portion united thereto at the point where said yielding is greatest.

In testimony whereof, I have hereunto subscribed my name this 28th day of July, 1926.

JURJEN S. HIGH.
